[57] CLAIM

The ornamental design for a tanning booth, as shown and described.

DESCRIPTION

FIG. 1 is an isometric view of a tanning booth according to my invention looking at the top and left side and with the door open;

FIG. 2 is an isometric view similar to FIG. 1, but showing the door closed;

FIG. 3 is an isometric view of my tanning booth looking at the top and right side thereof; and,

FIG. 4 is an isometric view thereof looking at the bottom and rear thereof.

FIG. 1

FIG. 4

FIG. 3

FIG. 2
